(57) CLAIM

The ornamental design for a minimalist wallet, as shown and described.

DESCRIPTION

FIG. 1 is a front perspective view of the minimalist wallet.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof.

FIG. 8 is a rear perspective view thereof; and,

FIG. 9 is a front perspective view of the minimalist wallet in an alternative position.

The broken lines present in the drawings defining an opening in a panel of the minimalist wallet form no part of the claimed design.
